TACHOMETER

Donald Lane, Trevose, Pa., assignor to Hurst-Campbell, Inc., Warminster, Pa., a corporation of Pennsylvania

Filed July 31, 1968, Ser. No. 12,977

Term of patent 14 years

Int. Cl. D10—08; D12—99
U.S. Cl. D52—6

Fig. 1.

Fig. 2.

Fig. 3.

Fig. 4.

FIG. 1 is a front perspective view of a tachometer embodying my new design.

FIG. 2 is a rear perspective view of the same.

FIG. 3 is a side elevational view of the same.

FIG. 4 is a bottom plan view looking in the direction of line 4—4 on FIG. 3.

The essential features of the design reside in the solid line portions.

What I claim is:

The ornamental design for a tachometer, as shown and described.
